Primary Examiner — Susan Moon Lee(74) *Attorney, Agent, or Firm* — Polsinelli Shughart PC**(57) CLAIM**

The ornamental design for a perch for a bird feeder, as shown and described.

DESCRIPTION

FIG. 1 is a front perspective view of a perch for a bird feeder embodying my new design.

FIG. 2 is a top view thereof.

FIG. 3 is a bottom view thereof.

FIG. 4 is a right end view thereof; and,

FIG. 5 is a left end view thereof.

The colors shown the figures are hereby disclaimed, forming no part of the claimed design.
